(57)

CLAIM

The ornamental design for a feral pig specific baiting station as shown and described.

DESCRIPTION

FIG. 1 is a perspective view of a feral pig specific baiting station, showing my new design;
FIG. 2 is a right side elevation view thereof;
FIG. 3 is a left side elevation view thereof;
FIG. 4 is a front elevation view thereof;
FIG. 5 is a rear elevation view thereof;
FIG. 6 is a top plan view thereof;
FIG. 7 is a bottom plan view thereof; and,
FIG. 8 is a bottom perspective view thereof.

1 Claim, 8 Drawing Sheets
